BUILDING WALL CONSTRUCTION

Edwin E. Slick, Pittsburgh, Pa.

Application August 17, 1937, Serial No. 159,454

20 Claims. (Cl. 72—41)

This invention pertains to building blocks or bricks, and more particularly, to blocks having an opening closed off by a facing member.

In one aspect, my invention pertains to a hollow building wall construction having a facing thereon capable of transmitting light.

It has been an object of my invention to provide a new and improved form of building block, and especially, to provide a new and improved building block that is capable of transmitting light therethrough.

Another object of my invention has been to provide an inexpensive and/or practical form of hollow building block.

15 A further object has been to devise a building block having substantially the desired light transmission properties of a glass building block without the disadvantageous features thereof.

A still further object of my invention has been 20 to provide a wall construction that may be employed to take the place of the entire thickness of a building construction including facing members.

These and many other objects of my invention 25 will appear to those skilled in the art from the specification, the drawing, and the appended claims.

In the drawing:

Figure 1 is a side sectional view in elevation 30 of a wall constructed in accordance with the principles of my invention;

Figure 2 is a top sectional view taken along the line II—II of Figure 1;

Figure 3 is a side view in elevation of a block 35 unit such as employed in the embodiment of my invention shown in Figures 1 and 2;

Figure 4 is an end view of the block of Figure 3;

Figure 5 is an end sectional view taken along the line V—V of Figure 3;

40 Figure 6 is an end view in perspective showing the inside construction of a facing member constructed in accordance with my invention;

Figure 7 is a horizontal sectional view similar to that of Figure 2 through a modified form of block unit constructed in accordance with the principles of my invention;

Figure 8 is a horizontal sectional view similar to Figure 2 showing a modified type of facing arrangement; and

50 Figure 9 is an end sectional view similar to that of Figure 5 showing a modified form of block.

In carrying out my invention, I preferably provide a hollow building unit or block 10 having suitable openings therein or extending there-

through. Suitably designed facing members or elements 15 are provided with projecting or attaching portions 16 that are adapted to cooperatively engage inner portions of the walls 11 and 12 of the block adjacent side or end faces thereof.

The construction and arrangement are preferably such that the hollow block 10 may be formed in a single operation by running it through a pug mill. In other words, the facing elements 15 are constructed and/or mounted in such a manner that I have no need for recessed, offset, or panelled wall portions. Thus, the wall portions will extend continuously and unbrokenly from one side or end of the block 10 to the other, and no special and/or additional operation is necessary to adapt the block to the facing members 15.

The facing members or elements 15 are mounted in such a manner that their edge portions are free to expand and contract without hindrance. 20 That is, the adjacent edges of mounted elements 15 preferably have a spaced-apart relationship with respect to each other and, of course, are not confined by wall portions of the block, itself. It will thus be apparent that the face or panel members 15 of glass or similar construction are located beyond what may be termed "load-carrying planes of the block." In other words, the panel elements 15 are mounted beyond limiting or confining wall portions of the block, and for 25 this reason, are protected from the load to which the main wall portions of suitable ceramic or cementitious or other load-carrying material are subjected.

In the form of unit chosen for the purpose of 30 illustration, the block 10 has a rectangular shape bounded by outer wall portions 11, and reinforced and joined together by a reinforcing or central partition portion 12. The block may be made from any suitable material, such as clay, cement, 35 rubber, plastic, wood, metal, etc., but is preferably made of a ceramic or cementitious material.

The panel portion 15 in like manner is preferably pressed out from a suitable plastic or viscous material, such as glass, transparent rubber, cellulose, etc. Primarily, therefore, the elements 15 are preferably of a character such that at least a portion of the light may be transmitted therethrough. That is, they are preferably at least translucent and may be transparent. I 45 also contemplate using opaque elements 15 along portions of the building construction where light is not needed.

It will be apparent to those skilled in the art 50 that the facing elements or members 15 may be

of transparent or colored material and may be clear or may have suitable designs thereon. Further, as shown in Figure 9, the panel 15 may have a reflecting surface 26.

5 From the above, it will appear that I have been able to provide a building block having a skeleton structure which may be advantageously set in place in a building construction, for example, by reason of its expansion and 10 contraction qualities, and also by reason of its porosity. Thus, the troubles encountered in mounting all-glass blocks are eliminated. On the other hand, the construction is such that substantially the same light-transmitting ability 15 may be imparted to a block by the utilization of transparent or translucent facing members or elements.

The material used and/or the structural parts employed in making the body portion of the 20 block 10 are preferably selected upon consideration of strength, cost, durability, and ease and/or effectiveness of joints. On the other hand, the selection of the material and structural parts of the facing elements 15 is preferably selected from the standpoint of the design 25 and/or light transmission effects desired. The association of the body portion and facing elements is such that individual deleterious effects are substantially eliminated and advantageous 30 features of both are coordinated and enhanced.

The facing elements 15, which are preferably 35 of glass construction, have suitable attaching portions 16 extending therefrom, see, for example, Figure 6. The attaching portions 16 may be of continuous, square, rectangular, circular, or oval shape, corresponding to the shape of the continuous inner wall portions of the block 10. In Figure 6, the portions 16 comprise opposite spaced-apart walls b-b and a-a. However, 40 suitable spaced-apart lugs or other constructions may be employed in this connection.

The facing members 15, as shown particularly in Figures 2, 5, and 7, are mounted upon edge or side faces of the block 10 in such a manner 45 that their edges terminate substantially centrally of the thicknesses of the wall portions 11 and 12. In this manner, an effective seal can be obtained and any suitable or specially-designed material may be employed for attaching 50 edge portions of the facing members with respect to each other or for filling up the spacing therebetween. In Figure 2, I have indicated an ordinary form of suitable cementitious material 21 as positioned between each block 10 which, 55 of course, comprises, as shown in Figure 3, a pair of windows or openings therein. The major portion of the stress and strain of the construction is thus borne by the strong material of the structure 10, rather than by the facing members 15 60 that ordinarily have the wrong type of expansion and contraction qualities.

The facing elements 15 may be mounted in position before or after the wall construction has been assembled, and if desired, they may 65 be merely frictionally held in position or may be further attached by some suitable cement. I prefer to employ the cement adjacent the flange 16, in order that each individual element 15 may be readily removed from the building block 70 construction, if necessary, by individually breaking it. Adjacent edges of the facing elements 15 may be left open, as shown in Figure 7, or as mentioned above, may be sealed by any suitable cementitious material or by a flexible, yieldable 75 material, such as a bituminous asphaltic com-

position, as set forth in my copending application Serial No. 119,785, entitled "Building blocks and procedure for making them."

By means of the present construction, I can also stagger one block with reference to another, 5 see Figure 1. It is, of course, apparent that a much better bond between blocks is thus made possible. The corner portions of the wall may be left blank or may be taken care of by a specially designed form of block, such as 10', see 10 Figure 2. The block 10' has a portion of its outside wall 14 cut away, leaving only a narrow rim portion 13. The back of the block, which is to lie adjacent an end wall of an adjacent block 10, is closed off, see the numeral 14, and 15 is beveled to connect with the partition portion 12'. It is, of course, apparent that an ordinary form of block 10 may be employed instead of the block 10' and in such case a portion of the wall 11 will face outwardly. 20

Since in an ordinary construction, the builder may wish to provide opaque wall portions, I contemplate either providing hollow block with front and back side faces having the same over-all dimension as the blocks 10 with their facing elements 15, or providing solid members of the same over-all cross-sectional width. Then, too, opaque panels 15 of any suitable material may be employed to accomplish the same result. It will be apparent that any suitable design may 30 be imposed upon the opaque as well as upon the transparent or translucent elements 15 or upon the side or end facing walls of the block if the elements 15 are omitted. 25

In Figure 7, I have shown a modified construction which provides a very effective form of block. One or more of the facing elements 15 may be provided with a cup-shaped element 17 for closing it off and providing one or more air spaces to improve the insulating qualities of the 40 block 10. The cup-shaped element 17 has suitably extending flanges 18 corresponding to the flanges 16; the flanges 16 and 18 are preferably fused together and slid into a cooperative relationship with the side walls of the block 10, as a 45 unit. See the fusing method set forth in my copending application above-mentioned. However, it will be apparent that the members 17 and 15 may be mounted individually and cemented in position, and that any suitable number of members 15 may be provided in each opening. For example, each of the opposite-facing members 15 may be provided with sealing-off elements 17. 50

Although I preferably make the facing elements 5 15 in such a manner that one or more may be mounted on the same block and the same side of the block, it will be apparent that larger elements may be employed. For example, one element can be used to cover all of the openings in a given block, or all of the openings or part of the openings of adjacent blocks of a wall construction. See, for example, Figure 8. Here, the facing member 15b is provided with side-attaching wall portions 16b for engagement with wall portions of a pair of blocks 10. If this arrangement is employed, I preferably eliminate one set of projecting portions a-a, see Figure 6 of the drawing. Of course, it will be apparent that the size of the facing element 15 or 15b will depend upon questions of practicability and also upon the type of design desired. I prefer the smaller elements, since they can be readily pressed into form and can be easily and quickly detached and 7

replaced when desired; they also are readily adaptable to design requirements.

In Figure 9, I have shown a block 20 whose back wall portion 22 is closed and whose front side is open to receive an element 15. A reflecting surface 26 may be provided on the element 15, as shown, or if desired, may be provided on the inner wall portions 21' and/or 22 of the block. If desired, the opaque wall portion 22 may be provided with any suitable configuration 23.

Where blocks 10 or 20 having double air spaces are used, such as shown in Figure 7 of the drawing, they are particularly suitable to take the place of a complete wall structure of a building.

In other words, the facing elements 15 take the place of inner and other facing members of an ordinary construction and may have any suitable design or inlay, as desired. The block portion 10 has suitable depth, air space characteristics, as well as strength such that it can take the place of a skeleton framework, sheathing, and other members employed in an ordinary construction. In this manner, I have been able to provide a very inexpensive but practical form of block that eliminates the complicated and extensive structure of an ordinary building and that may also take the place of ordinary windows if, for example, the building is to be air-conditioned. Bricks and other suitable building materials may be employed to build up the wall construction and the openings therein; the facing members are then mounted over the openings and over and upon the wall construction.

In referring to "side" or "end" portions of the block in the specification and claims, I include both terms broadly and interchangeably as portions of the block. The block of my invention may be said to have a composite construction.

Although I have shown preferred forms of my invention for the purpose of illustration, it will be apparent to those skilled in the art that other suitable arrangements may be employed and that various modifications, substitutions, additions, and/or subtractions, may also be made without departing from the spirit and scope of my invention as indicated in the appended claims.

I claim:

1. A building block having wall portions of a suitable load-carrying type of material, and a facing element of glass or similar material having a panel portion mounted upon surface portions of a side of the block, said panel portion being located beyond confining load-carrying portions of the block.

2. A building block having spaced-apart wall portions of a suitable load-carrying type of material terminating in an opening adjacent a side thereof, a facing element of glass or similar material having a panel portion mounted over the opening and upon outer surface portions of a side of the block, said panel portion being located beyond confining load-carrying portions of the block.

3. A building block having wall portions extending continuously and unbrokenly along a length thereof and therethrough, and a panel closing off the opening and resting upon face portions of the block, said panel being located beyond confining load-carrying portions of the block.

4. In a substantially hollow building block having a panel portion and suitable wall portions, a facing element having projecting attaching portions, said panel portion being adapted to rest upon outer side faces of said wall portions and

said attaching projections being adapted to cooperatively engage inner portions of said walls in such a manner that structural strain and load will be borne by said wall portions and that said panel portion will be protected with respect thereto.

5. In a substantially hollow building block having substantially continuous inner walls of uniform dimension along the opening therein, a facing element having a panel portion and attaching portions thereon, said attaching portions being adapted to cooperatively engage inner portions of said continuous walls and to hold said panel portion over the opening in said block and upon outer face portions of said walls, said panel portion being located beyond load-carrying portions of the block.

6. In a substantially hollow building block having at least one lateral light passage extending from an outer to an inner face thereof, facing elements having panel portions mounted over said light passage and upon adjacent wall portions of opposite outer faces of said block, said panel portions being at least translucent.

7. A building block provided with a pair of light openings extending therethrough, facing elements mounted over said openings and upon opposite faces of said block, said facing elements on one face of the block having a spaced-apart relationship with respect to adjacent elements on the same face, said facing elements having edge portions located beyond confining load-carrying portions of the block.

8. A building block having a pair of light passages extending therethrough and a partition member separating said passages, a pair of at least translucent facing elements having panel portions mounted over the passages on each side face of said block, said panel portions on one face of said block having a spaced-apart relationship with respect to each other and terminating substantially centrally of the block adjacent the thickness of said partition, said panel portions being located beyond confining load-carrying portions of the block.

9. A building block having at least one passageway therethrough at least substantially surrounded by wall portions, said passage terminating adjacent opposite faces of said block, a transparent facing element having a panel portion, attaching portions extending from said panel portion, said panel portion being mounted over said passageway and upon an outer face of said block, said panel portion being located beyond load-carrying portions of the block.

10. A building block of ceramic or cementitious material having a passageway extending therethrough from one face to another face thereof, and means closing off said passageway and extending inwardly thereof from a face of said block, and means associated with said first-mentioned means and providing a sealed air space with said closing-off means within said block that is independent of wall portions of said block.

11. In a substantially hollow building block having at least one chamber therein and terminating adjacent opposite face portions thereof, facing elements mounted over said chamber and upon opposite faces of said block, and an additional element mounted within said chamber in a substantially parallel relationship with respect to said facing elements and providing a pair of air spaces in said block.

12. In a substantially hollow building block having at least one chamber therein and termi-

- nating adjacent opposite face portions thereof, facing elements mounted over said chamber and upon opposite faces of said block, and an additional element mounted within said chamber in a substantially parallel relationship with respect to said facing elements and providing a pair of air spaces in said block, said means being sealed with respect to at least one of said facing elements.
13. In a substantially hollow building block of ceramic, cementitious, or other suitable material having spaced-apart portions therein opening to at least one face thereof, a facing element having a panel portion mounted over said spaced-apart portions and upon the adjacent face of said block, and means providing a reflecting surface within the spaced-apart portions of said block, said panel portion being located beyond load-carrying portions of the block.
14. In a substantially hollow building block of cementitious, ceramic, or other suitable load-carrying opaque material, at least one passageway in said block, a partition in said passageway, a side portion of said block being left open, a support portion extending about said last-mentioned side portion of said block, and facing elements having panel portions mounted over said passageway upon outer faces of said element and said support portion and closing off said open wall portion of said block, said panel portions being located beyond load-carrying portions of the block.
15. In a building wall construction, a pair of blocks mounted in an adjacent and staggered relationship with respect to each other, each of said blocks being of substantially hollow construction and having an air space therein, and at least translucent means positioned on opposite outer faces of said blocks adjacent said air spaces, said means having panel means positioned beyond load-carrying portions of the block.
16. In a complete wall structure for a building construction, a plurality of adjacently-positioned blocks mounted in a substantially staggered relationship with respect to each other, each of said blocks having at least one passageway therein extending through opposite faces thereof from an inner portion of the building to an outer portion thereof, and transparent facing elements mounted upon outer faces of said blocks and over the passageways therein, said facing elements terminating substantially adjacent wall thickness portions of said blocks, and means holding said facing members in position with respect to said blocks and said blocks in position with respect to each other, said facing elements having panel portions positioned beyond load-carrying portions of the block.
17. In a building wall having load-supporting side wall portions and openings therebetween, a panel of glass or similar material covering the openings, said panel having means interfitting with said side wall portions and mounting said panel upon a plane representing outer surface portions of a side of the building wall, said panel being positioned beyond load-carrying portions of the wall.
18. In a building wall having load-supporting structural side wall portions and an opening extending from one face thereof to another face thereof between said side wall portions, a glass facing member having a panel portion mounted over the opening and upon outer face portions of said side wall portions, said facing member having means interfitting with said side wall portions and positioning said panel portion beyond load-carrying portions of the wall.
19. In a building wall as defined in claim 17, means of glass or other suitable material cooperating with said interfitting means and said panel to provide a closed-off air space with said panel.
20. In a building block as defined in claim 1, means cooperating with said facing element to provide a closed-off air space within the block.

EDWIN E. SLICK.
